Primary Examiner — Omeed Agilee(74) *Attorney, Agent, or Firm* — Birch, Stewart, Kolasch & Birch, LLP(57) **CLAIM**

The ornamental design for a culture container, as shown and described.

DESCRIPTION

FIG. 1 is a front view of a culture container in accordance with the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a cross sectional view taken along line 9-9 of FIG. 1;

FIG. 10 is a cross sectional view taken along line 10-10 of FIG. 1; and,

FIG. 11 is a cross sectional view taken along line 11-11 of FIG. 4.
